UNITED STATES PATENT OFFICE.

JOHN W. LESLIE, OF EVANSTON, ILLINOIS, ASSIGNOR TO SIGNODE SYSTEM, INC., OF CHICAGO, ILLINOIS, A CORPORATION OF DELAWARE.

BALE TIE.

Application filed March 13, 1922. Serial No. 543,155.

To all whom it may concern:

Be it known that I, JOHN W. LESLIE, a citizen of the United States, and resident of Evanston, in the county of Cook and State 5 of Illinois, have invented a certain new and useful Improvement in Bale Ties, of which the following is a full, clear, concise, and exact description, reference being had to the accompanying drawings, forming a part of 10 this specification.

When a wire bale tie of any one of the types heretofore employed is applied to a rigid box or similar package, the tie is apt to be somewhat loose for the reason that 15 the workman applying same has no way of determining the limit to which it may be safely stretched. If such a tie is stretched too tightly it will break or become overstrained, and thus unreliable. Ordinarily, 20 a workman applying a wire bale tie being apprehensive of breaking or overstraining the tie fails to stretch the tie to the most desirable extent. This is especially true when the workman uses certain types of wire 25 stretching tools in which the direct stretching pull is supplemented by the rotation of the entire tool around an axis located substantially at the loop of the tie. This second operation applies tension to the tie 30 under considerable leverage and in those cases where the primary stretching operation has been carried too far the tie will break in this secondary operation. This is a very frequent source of tie breakage.

35 My invention contemplates the provision of a wire tie which is so constructed that it will yield somewhat when it has been subjected to a tensile stress slightly less than that required to overstrain it. A workman 40 applying a wire tie of this character may stretch the same to the desired degree of tightness without fear or apprehension of breaking or overstraining it.

45 In the accompanying drawings illustrating my invention—

Figure 1 illustrates one of the ties of my invention extending around a box and ready to be tightened thereon;

50 Figure 2 is a fragmentary plan view on an enlarged scale of the ends of the tie shown in Figure 1;

Figure 3 is a view similar to Figure 2; but illustrating the preformed loop of the tie as it appears after the tie has been

stretched to a degree slightly less than that 55 required to overstrain it;

Figure 4 shows the ends of the tie as they appear after the formation of the second loop, and

Figures 5, 6 and 7 are views similar to 60 Figures 2, 3 and 4, but illustrating a modified embodiment of my invention.

Similar characters of reference refer to similar parts throughout the several views.

Referring first to Figure 1, at A I have 65 illustrated a box or carton around which one of my improved wire ties has been extended. The tie is indicated at B. It will be noted that one end of the tie has been 70 conformed and twisted upon itself to provide an eye or loop C. The eye or loop C is formed prior to the application of the tie to the package, and will usually be made by the manufacturer of the wire tie rather than 75 by the user thereof.

Referring now to Figure 2, it will be 80 noted that the eye or loop C as there shown is substantially heart shaped. The important features of the loop, however, are the abrupt angle bends c—c. I have found that when my improved tie is stretched in the manner hereinafter described, the eye or loop C will retain the shape shown in Figure 2 until the tie has been subjected to a tensile stress just slightly less than that required to overstrain it. When the tensile 85 stress to which the tie is subjected becomes just slightly less than that which will result in the tie being overstrained, the abrupt angle bends c—c open. In applying my im-

proved tie to a package of the type illustrated in Figure 1, the end D of the tie is passed through loop C and is drawn up to stretch the tie until the abrupt angle bends 90 c—c open as illustrated in Figure 3. The workman thereupon twists the tie end D upon itself to form a second loop E which interengages with the loop C. The tie has 95 now been properly tightened, and applied to the package. I contemplate that a suit-

able tool or tools will usually be employed for stretching the tie and for forming the second loop E. Tools suitable for my purpose are now known to persons familiar with the art to which my invention relates— 100 hence it will be unnecessary for me to illustrate or describe such tools.

It is satisfactory to have the abrupt angle

bends *c-c* open just slightly before the tie has been stretched to the extent necessary to overstrain it; because when the bends *c-c* open the preformed loop C lengthens 5 slightly and therefore, to a small extent, relieves the tension under which the tie has been placed.

The embodiment of my invention illustrated in Figures 5, 6 and 7 differs from 10 that shown in the preceding figures in that the preformed loop C is initially triangular in shape, in this case it being the base of the triangle which is engaged by the tie end D when the latter is drawn through the preformed loop. The abrupt angle bends *c-c* serve the same purpose in both of the illustrated embodiments of my invention.

I do not limit myself to the particular embodiments of my invention herein shown 20 and described, as I appreciate that my invention may be variously modified without departing from the scope of the invention covered by the appended claims.

What I claim is new and desire to secure 25 by Letters Patent of the United States is:

1. The method which consists in passing

around a package a wire tie having one end thereof conformed and twisted upon itself to provide a polygonal loop, drawing the unlooped end of the tie through said polygonal loop until said polygonal loop becomes appreciably narrower, and then twisting the unlooped end of the tie upon itself to form a second loop which interengages with the first-mentioned loop. 30

2. The combination with a package, of a tie wire encircling said package, one end of said wire having a loop formed with abrupt angle bends therein, and a loop on the other end of said wire interengaging with said first loop, said second loop being formed by passing the end of said wire through said first mentioned loop and then twisting said wire back upon itself, the abrupt angle bends in said first loop indicating by their 40 angle the tension of said tie wire.

It witness whereof, I hereunto subscribe my name this 6th day of March, 1922.

JOHN W. LESLIE.
